CLARENCE D. TUSKA, OF HARTFORD, CONNECTICUT, ASSIGNOR TO THE C. D. TUSKA COMPANY, OF HARTFORD, CONNECTICUT, A CORPORATION OF CONNECTICUT.

DIAL KNOB.

Application filed June 17, 1922, Serial No. 569,085. Renewed December 16, 1924.

To all whom it may concern:

Be it known that I, CLARENCE D. TUSKA, a citizen of the United States, residing at Hartford, in the county of Hartford and State of Connecticut, have invented new and useful Improvements in Dial Knobs, of which the following is a specification.

This invention relates to dial knobs such as are used in connection with various kinds of radio and electrical apparatus for adjusting rotatable parts thereof.

The object of the invention is to provide certain new and useful improvements in the construction of molded dial knobs tending to prevent warping and to secure lightness and strength with economy of manufacture.

The invention consists in the improved dial knob hereinafter described and claimed.

In the drawings,—

Fig. 1 is a front elevational view of a dial knob constructed in accordance with the present invention;

Fig. 2 is a side elevational view of the dial knob;

Fig. 3 is a rear elevational view thereof;

Fig. 4 is a section taken on the line 4—4 of Fig. 3; and

Fig. 5 is a fragmentary sectional view taken on the lines 5—5 of Fig. 3.

Referring to the drawings, the illustrated dial knob comprises a central knob portion 6 and an integral dial portion 7, the whole being molded from suitable dielectric material. As shown, the knob portion 6 is peripherally knurled as indicated at 8, and the dial portion 7 has the usual bevelled margin bearing a vernier 9 that is adapted to cooperate with a suitable mark (not shown) upon a stationary part of the apparatus.

Dial knobs of this general character, as heretofore constructed have been liable to warp more or less with age by reason of the unequal distribution of the mass of material of which they are composed, the warping resulting in lateral distortion of the dial portion. Inasmuch as the dial portion carries the vernier it is particularly desirable that it should be free from lateral distortion so that it will not wobble as it rotates.

In accordance with the present invention the dial knob is molded in such a shape as to secure a substantially uniform distribution of mass throughout the entire molded article. To this end the dies employed for

molding the dial knob are constructed and arranged to produce central recesses in both the front and rear faces of the knob portion. The recess in the front face of the knob is indicated at 12 in Figs. 1 and 4 and is shaped and proportioned as clearly shown therein. The recess at the rear of the knob is indicated at 14 in Figs. 3 and 4 and is in the form of an annular channel concentric with the axis of the knob. The above described recessed construction provides a transverse web 15 intermediate the front and rear faces of the dial knob and a central hub 16 which projects rearwardly from the web 15 to a plane flush with the rear face of the dial knob. The hub 16 is provided with an axial cylindrical recess or bore 18 for receiving the shaft or trunnion of the part to be rotatably adjusted. An internally screw-threaded bushing 20 (Fig. 4) may be anchored in the central recess 18 to receive external screw-threads upon the shaft of the adjustable part.

By reference to Fig. 4 it will be apparent that a practically uniform distribution of the molded mass is obtained by virtue of the substantially skeleton-like construction afforded by the arrangement of the recesses 12, 14 and 18. By constructing the dial knob in the improved manner above described the objectionable warping or distortion of the dial is materially reduced if not entirely eliminated. The recessed construction also materially reduces the weight of the knob and tends to lessen any possible capacity effect of the knob upon the apparatus with which it is associated, thus being a feature of some importance when the dial knob is used in connection with certain kinds of radio apparatus. Obviously a considerable saving of material is effected by reason of the recessed construction.

Dial knobs, in common with other molded articles of a similar character, are usually ejected from the die in which they are molded by means of an ejector which is movable vertically through the base of the die. Such ejectors engage the lowermost face of the molded article during the molding operation and even though such an ejecting plunger is made flush with the bottom of the mold it inevitably makes a mark or scar on the molded article during the molding operation. In the case of a dial knob, the front face thereof is lowermost

in the mold and consequently it is this front face which is engaged by the ejector. Since the front face of the knob is exposed to view when the knob is in use it is particularly desirable that its surface should be finished smoothly and should be free from any disfiguring mark such as that produced by the ejector.

By shaping the mold so that the recess 12 is formed in the front face of the dial knob, it is practicable to make the ejecting plunger of a diameter equal to that of the recess to be formed in the dial knob and to locate said plunger in the die so that its upper end 15 will normally project into the die sufficiently to form the desired recess therein. Then when the ejecting plunger is subsequently elevated to eject the finished article from the mold it will raise said article by engagement throughout the entire area at the base 20 of the recess in its lower face and as a result the finished surface of the article will not be marred or disfigured in any way. Furthermore, the provision of the recess 25 12 in the front face of the dial knob greatly improves the appearance of the article and thus renders it more readily salable.

It is often desirable to limit the range of rotation of the adjustable part to which the 30 dial knob is attached. With this end in view, the present invention contemplates the forming of one or more radial ribs or webs 22 across the annular recess 14 of the dial knob and the provision of a stop lug such 35 as indicated at 23 in Fig. 4, this lug projecting from a panel or other stationary part 24 and being adapted to extend into the recess 14 in the dial knob in position to coact with the web or webs 22. The stop webs 22 40 are molded integrally with the rest of the dial knob and may be located in predetermined positions to limit rotation of the dial to a desired number of degrees.

In certain combinations of radio apparatus where there are two or more parts to be 45 rotatably adjusted by means of dial knobs it is desirable to limit in different degrees the movements of the several parts. In order that the ranges of rotational movements of different parts may be limited to 50 different extents without the necessity of providing separate dial knobs in which the stop webs are arranged in different relative positions, the present invention contemplates the construction and arrangement of 55 the stop webs 22 in such a manner that a single dial knob having at least two stop webs is capable of being positioned relatively to the stop lug 23 so that either of 60 two or more different ranges of rotational adjustment may be provided for as may be required. In the preferred form of the invention illustrated in the drawings, the stop webs 22 are positioned to divide the annular recess or channel 14 into a relatively

short portion 25 and a relatively long portion 26. The arrangement and proportions of the webs 22 and of the stop lug 23 are such that when the dial knob is so located radially with respect to said stop lug that 70 the latter projects into the short portion 25 of the channel 14, the range of rotational adjustment of the dial will be limited to 90° and when the dial knob is so located that the stop lug 23 projects into the long portion 75 26 of the channel 14, the range of rotation of the dial will be limited to 180°. Various ranges of rotation may be provided for by arranging stop webs in the recess 14 so as to provide arcuate channels of varying 80 lengths which may be selectively arranged for cooperation with a single fixed stop lug. Obviously by this expedient dial knobs of identically the same design may be employed in connection with different adjustable parts 85 to provide for different limits of rotational adjustment. The radial stop webs 22 also serve to stiffen and reinforce the dial knobs and thus render them less liable to breakage. 90

The invention having been described, what is claimed and desired to be secured by Letters Patent is—

1. A dial knob comprising a substantially cylindrical central knob portion and a peripheral dial portion disposed at right angles to the rotational axis of the dial knob, the whole being integrally formed of molded dielectric material and the opposite end faces of the knob being recessed to effect 100 a substantially uniform distribution of the mass of molded material. 95

2. A dial knob comprising a substantially cylindrical central knob portion and a peripheral dial portion disposed at right angles to the rotational axis of the dial knob, the whole being constructed of molded dielectric material and having a central recess in its rear face adapted to receive a shaft or like part and a deep annular channel concentric with said recess for securing a 105 more nearly even distribution of the mass of material in the dial knob. 110

3. A dial knob for attachment to the shaft or trunnion of a rotatably adjustable element comprising integral knob and dial portions and having an annular channel in its rear face concentric with the periphery of the dial portion, and radial webs extending across said channel for coacting with a fixed stop to limit the range of rotation of the dial knob, said webs being relatively arranged to limit the rotation of the dial knob to one extent when the stop is operatively associated with the portion of the channel at one side of said webs and to limit said rotation to a different extent when the stop is operatively associated with the portion of the channel at the other side of said webs. 115 120

4. A dial knob for attachment to the shaft 130

or trunnion of a rotatably adjustable element comprising integral knob and dial portions and having an annular channel in its rear face concentric with the periphery of the dial portion, and radial webs extending across said channel for coacting with a fixed stop to limit the range of rotation of the dial knob, said webs dividing said channel into segments of different lengths and being 5 portioned with respect to said stop to limit the rotation of the dial knob to a quarter turn when said stop member is operatively associated with the shorter segment of the channel and to limit the rotation of the dial 10 knob to a half turn when said stop member is operatively associated with the longer segment of said channel.

5. A dial knob comprising a substantially cylindrical central knob portion and a peripheral dial portion disposed at right angles to the rotational axis of the dial knob, the whole being constructed of molded dielectric material and having a deep annular channel in its rear face and radial ribs 20 extending across said channel for stiffening and reinforcing the structure.

6. A dial knob comprising a substantially cylindrical central knob portion and a peripheral dial portion disposed at right angles to the rotational axis of the dial knob 30 the whole being constructed of molded dielectric material and having a central recess in its rear face adapted to receive a shaft or like part, the knob having also an annular channel in its rear face concentric with said recess and a plurality of spaced apart strengthening ribs extending across said channel.

7. A dial knob comprising a substantially cylindrical central knob portion and a peripheral dial portion disposed at right angles to the rotational axis of the dial knob, the whole being constructed of molded dielectric material and having a central recess 40 in its rear face adapted to receive a shaft or like part, an annular channel in said rear face concentric with said recess, and stops in said channel for cooperating with a fixed stop to limit the rotation of the dial knob.

In testimony whereof I have affixed my 45 signature.

CLARENCE D. TUSKA.
